David J. Spargo, 963 Hartford Turnpike,
Hamden, Conn. 06517

Filed Sept. 16, 1968, Ser. No. 13,544

Term of patent 14 years

Int. Cl. D12—14

U.S. Cl. D14—6

FIG. 1 is a perspective view of a handle for an automobile shift lever or similar article, showing my new design; and

FIGS. 2, 3, 4, 5 and 6 are right-side, front, top, rear and left-side views, respectively, thereof.

The shift lever, shown fragmentarily and in broken lines in FIGURE 1, is included for illustrative purposes only.

I claim:

The ornamental design for a handle for an automobile shift lever or similar article, substantially as shown and described.
